UNITED STATES PATENT OFFICE

105,795

DESIGN FOR A LAMP SHADE OR SIMILAR ARTICLE

Paul W. Jenkins, Corning, N. Y.

Application June 28, 1937, Serial No. 70,103

Term of patent 7 years

To all whom it may concern:

Be it known that I, Paul W. Jenkins, a citizen of the United States of America and a resident of Corning, in the county of Steuben and State of New York, have invented a new, original, and ornamental Design for a Lamp Shade or Similar Article, of which the following is a specification, reference being had to the accompanying drawing, forming part thereof, in which:

Figure 1 is a side view in elevation of a lamp shade or similar article showing my new design; and

Figure 2 is a bottom plan view of the same.

This invention resides in a bell shaped reflector

body having surrounding its lower end a plurality of equally spaced annular ribs extending up for approximately one-third of its height while the upper flaring portion of the unit is provided with external flutes each of which terminates at its upper edge in equally spaced arcuate projections forming a uniformly fluted edge at the periphery of the upper end of the bowl.

I claim:

The ornamental design for a lamp shade or similar article substantially as shown and described.

PAUL W. JENKINS.
